UNITED STATES PATENT OFFICE.

ROBERT WINBERG, OF PROVIDENCE, RHODE ISLAND.

DESIGN FOR A RING.

Application filed July 8, 1925. Serial No. 14,026. Term of patent 3½ years.

To all whom it may concern:

Be it known that I, ROBERT WINBERG, a citizen of the United States, residing at Providence, in the county of Providence and State of Rhode Island, have invented a new, original, and ornamental Design for a Ring, of which the following is a specification, reference being had to the accompanying drawing, forming part thereof.

In the drawing:—

I claim:—

The ornamental design for a ring, as shown.

ROBERT WINBERG.
